UNITED STATES PATENT OFFICE.

GEORGE VALIANT, OF TORONTO, CANADA, ASSIGNOR TO MARGARET VALIANT, OF TORONTO, CANADA, AND WILLIAM MITCHENOR PENTELOW, OF LONDON, CANADA.

BICYCLE-CANOPY SUPPORT.

SPECIFICATION forming part of Letters Patent No. 710,726, dated October 7, 1902.

Application filed August 7, 1899. Serial No. 726,452. (No model.)

To all whom it may concern:

Be it known that I, GEORGE VALIANT, gentleman, of the city of Toronto, in the county of York, in the Province of Ontario, Canada, have invented certain new and useful Improvements in Bicycle-Umbrellas, of which the following is a specification.

My invention relates to improvements in bicycle-umbrellas patented to me in the Dominion of Canada under No. 60,765 on the 3d of August, 1898, and filed in the United States Patent Office under Serial No. 676,905 on the 8th of April, 1898; and the object of the invention is, first, to devise a simple support for connecting the main standard to the frame of the bicycle; secondly, to provide means whereby the main standard may be readily lengthened vertically and yet rigidly held from turning; thirdly, to provide a radially-adjustable means whereby the umbrella may be angled to any desired and convenient slant by the rider; fourthly, to devise an improved mechanism whereby the supporting-arms may be spread apart to hold the umbrella open or drawn together to hold it closed; fifthly, to provide an improved means for lengthening the supporting-arms of the umbrella, and, sixthly, to provide an improved and simplified form of umbrella. To accomplish these various objects, I have constructed and arranged the various parts of my invention as shown in the drawings and particularly described in detail in the following description.

Figure 1 is a perspective view of a portion of a bicycle, showing my improved bicycle-umbrella secured in position on the upper reach. Fig. 2 is a side elevation of the umbrella closed. Fig. 3 is a sectional perspective detail, intermediately broken away, of the telescopic standard. Fig. 3^a is a cross-sectional detail through the telescopic standard, showing the means for holding it in position and the form adapted for a gentleman's bicycle. Fig. 3^b is a similar view to Fig. 3^a, but showing the form adapted for a lady's bicycle. Fig. 4 is a detail of the spreading device for the arms. Fig. 5 is a detail of the toothed catch for adjusting the slant of the umbrella from front to rear and laterally. Fig. 6 is a perspective detail of the telescopic support-

ing-arm for the umbrella and the top adjustment for tilting the umbrella. Fig. 7 is a perspective detail, mostly in section and intermediately broken away, to show the construction of the umbrella and side bars thereof. Fig. 8 is a cross-section of the umbrella and side bars. Fig. 9 is a detail of the clip particularly adapted for a gentleman's bicycle to hold the standard in position.

In the drawings like characters of reference indicate corresponding parts in each figure.

A is the upper reach of the bicycle.

B is the clip, which is made in two parts B' B', having the semicylindrical portions b to fit over the top reach. The bottom parts b' of the clips have the opposing grooves b'.

2 is a bolt extending through the portions B' B' below the grooves b' and provided with a tightening-arm 3, fitting on the threaded end thereof. The upper part of one portion B' is provided with a recess b² and the other portion B' with a hole through which extends a stem c into the toothed block C, fitting into the corresponding recess b². At the end of the stem is provided a knob C', between which and the portion B' on the spindle C extends the spiral spring c', which is designed to hold the toothed block C in engagement with the toothed quadrantal end e of the short standard E. The short standard is pivoted at the bottom on the bolt e'. By pushing in upon the knob C' the toothed block C is removed from engagement with the quadrantal end e of the short standard E, which then can be set at any desired angle. By releasing the knob C' the toothed block recedes back into position, thereby rigidly holding the standards. The top reach A is also provided with a clip B², hinged at b³ and provided with opposing interior grooves b⁴ in the depending portions B³ B³.

D is a bar connected to the lugs a on the clip A' by the pin a' and extending through the grooves b' and b⁴. The portions B' B' are securely clamped upon the bar by the tightening-arm 3, and the portions B³ of the clip B² have one pin b⁵ extending through the bar and another pin b⁶ extending through the portion B³ underneath the bar, as indicated.

By the construction above described I am

enabled to hold the clip upon which the short standard is held rigidly in position and without any liability of it turning upon the upper reach.

5 The short standard E has inserted therein the lower end of the tubular elbow F, and the short standard is split at e^2 , as indicated. A circular clip G is provided, which has outwardly-extending lugs g^2 , connected together 10 by a tightening-bolt g' . By means of this clip the elbow is held securely in position from turning. It will of course be understood that the top of the elbow may be thrown on a line with the top reach of the frame of 15 the bicycle, or it may be angled laterally in relation to the top reach. The outer end of the elbow is provided with a clip H, having the projecting lugs h and tightening-bolt h' . Within the clip fits the lower portion I of the 20 main tubular standard, which has attached to or forming part of it the clip I', having the lugs i and tightening-bolt i' . This is substantially the same form as the other clips on the standards. The lower tubular portion I 25 of the main standard has a longitudinal projection i^2 , provided with a groove i^3 .

The clip H is provided with a sleeve h^2 , having a longitudinal slit or an opening h^3 , into which fits the longitudinal projection i^2 30 of the tubular portion I. The sleeve h^2 is provided with an annular groove h^4 , into which extends a set-screw h^5 , which is screwed through the clip-socket H, thereby securing the sleeve h^2 from vertical displacement.

35 I^2 is the telescopic extension of the standard I, which is provided with a longitudinal projection or key which fits within the groove i^3 , formed in the longitudinal projection i^2 of the standard I. As the clip H can be tightened 40 so as to retain the boss securely in position from turning, it will be seen that the tubular standard I and its extension I^2 will likewise be prevented from turning.

In order to adjust the extension I^2 within 45 the portion I, I provide the following device: I^3 is the closing-cap of the extension-tube I^2 . The cap I^3 is provided with a threaded hole i^4 , through which extends the threaded tube I^4 , which has connected to it at the top in order 50 to hold it steady, by the screw i^5 , the annular plate I^5 . The bottom of the tube is provided with an annular cone enlargement I^6 , between which and the cups i^6 fit the balls i^7 , forming a ball-bearing for turning the 55 threaded adjusting-tube. By so turning the adjusting-tube it will be readily understood that as it extends through the threaded hole i^4 of the closing-cap I^3 the standard may be lengthened or shortened the predetermined 60 distance necessary to raise or lower the umbrella for the height of different people.

In order to provide for the turning of the threaded tube i^4 , and thus effect the lengthening of the standard I, I provide a jointed 65 rod J, which at the inner end is provided with a collar j and a spring j' to hold the rod up in the adjusting-tube i^4 . The free parts

of the rod J are hinged and jointed together, as indicated in the drawings, and extend at the bottom through the internal collar j^2 , 70 which forms a stop for the rod when it is thrown through the notch j^3 into the crank position indicated in dotted lines in Fig. 3. In this figure also it will be seen that the inner rib i^8 of the extension-tube is provided 75 with a downward extension i^9 , which as soon as the adjusting-tube has been turned around sufficiently so as to bring it down into the lowermost position forms a projection in the pathway of the crank, which prevents its further rotation, and thus prevents stripping the thread of the screw on the adjusting-tube or otherwise deleteriously affecting or straining the construction, which there would be a tendency to do seeing there is a collar on the 80 end of the adjusting-tube. Under ordinary circumstances, however, the adjusting-tube may be readily turned to lengthen out the tube.

In Fig. 3^b I show the form of clip and extension thereof to be used in a lady's wheel instead of the elbow F in a gentleman's wheel. This simple device consists of a tubular extension F', which is fastened to the saddle-bar of the lady's wheel by set-screws f'. 90

The top of the extension-tube I is provided with substantially circular end plates K, within which is pivoted by the pin k the quadrantal end l of the extension-joint L. The extension-joint L is provided with arc-shaped 100 flanges l', as indicated, and the quadrantal end l is designed to engage with the toothed block k', fitting in the recess k² in the plate K and having the extension-spindle and knob and spring operated identically the same as 105 the toothed block C and its coacting parts, hereinbefore referred to. By means of the quadrantal end L and the toothed block k' the umbrella may be tilted sidewise into any desired position, depending upon the direction of the wind or the location of the sun. 110

At the top of the extension-joint L, I form the jaw-plates l², which receive the toothed quadrant M, which is suitably pivoted upon the pin l³. The toothed quadrant M forms 115 part of the tube M' and is engaged by the toothed block m, operated in precisely the same manner as the block C and its coacting parts hereinbefore described so as to tilt the supporting-arms, and thereby the umbrella, 120 to any desired slant or pitch desired by the rider and necessary for the exigencies of wind, rain, or sun.

The umbrella is a collapsible or, more properly, one that rolls up, and it is necessary in 125 order to roll it to provide a means for adjusting the supporting-arms N N to and from each other, which are pivotally connected to lugs m', situated diametrically opposite each other on the enlargement of the tube M', and for 130 this purpose I provide the following device: The tube M' is provided with an extension-tube M², which fits, preferably, within the same and is provided with a bottom inter-

nally-threaded flange m^2 and the top double jaws m^3 m^4 , which are connected by pins m^4 to lugs m^5 , which extend through slots n in the supporting-arms N , to which they are 5 pivotally connected by the pins n' , extending through the arms, which are preferably tubular. M^3 is a threaded adjusting-tube which has an annular cone enlargement m^3 near the bottom end thereof, forming, together with 10 the cups m^4 m^4 and the balls m^5 , a double ball-bearing. The tubular threaded adjusting-tube extends through the internally-threaded flange m^2 at the bottom of the tube M^3 and is provided with a rectangular hole m^6 and a 15 crank-spindle m^7 , constructed precisely and designed to be operated in precisely the same manner as the crank-spindle J and its accompanying parts connected to the adjusting-tube I^4 , hereinbefore described. By screwing 20 the adjusting spindle or tube upwardly of course the arms are thrown farther apart at the ends, and consequently the umbrella is spread out and by the reverse motion the ends of the arms are drawn together. The 25 supporting-arms are also arranged to telescope the bottom portion N' , being provided with a ring n' , having a spring extension n^2 , provided with a pin n^3 . The end of the spring n^2 is formed in the shape of a lip, so that the 30 spring can be sprung so as to withdraw the pin from one of the series of holes n^4 in the extension-tube N^2 . By this simple means the longitudinal adjustment of the arms is provided for. Near the top of the extension-tube N^2 of the supporting-arm I secure 35 another ring n^5 with the spring extension n^6 , having an end lip and pin n^7 , which extends into a hole o in the internal sleeve O . The internal sleeve O is provided with a large 40 head O' , having an end ring O^2 , in which fits the trunnion P . One end of the trunnion P is provided with a reduced end p , on which fit the washer p' and nut p^2 and by which the trunnion is held in position and yet permits of rotation within the ring O^2 . The top 45 of the trunnion has a right-angular extension p^3 , to which is connected, by the pin p^4 , the cross-bar Q through a lug q . At the end of the cross-bar are provided divided rings q' , which 50 are secured to the cross-bar by downwardly-extending screw-pins q^2 , attached to or forming part of the divided rings and held in position by the nuts q^3 underneath the end enlargements q^4 at each end of the cross-bar. The 55 device above described is necessary in order to tilt the umbrella without interfering with the standards or supporting-arms, which may be necessary in some cases.

In order to hold the cross-bars, and consequently the umbrella at the top of them, in any desired position in which they may be tilted, I provide in the enlargement O' of the internal sleeve O an internal plug 4 , through which extends the pin 5 . The pin 5 extends 60 through slots 6 in the enlargement O' , and the plug 4 is provided with an upwardly-extending pin 7 , which is designed to fit into one of

a series of holes 8 in the periphery of the trunnion P . The plug is held in position by a spiral spring 9 , extending below it and abutting the bottom turned-in edge of the internal sleeve O . A knurled ring 10 is connected to the pin 5 at the outside, and by this means the pin 7 may be withdrawn from engagement with one of the holes 8 and the trunnion may be turned so as to tilt the cross-bar, and consequently the umbrella. When in the desired position, the spring 9 will force the pin 7 into position in one of the holes, and thereby securely lock the umbrella at the 80 angle set.

R and R' are the side bars of the umbrella, such side bars being supported by the divided rings q' , forming part of the bar Q . The side bar R is a tubular one and is provided with a longitudinal slot r , and the side bar R' is a D-shaped bar formed from a tube, as indicated. The concave center of the bar R' is provided with a longitudinal slot r' , in which is fitted the end of the umbrella-web S , such end being securely held in position between the two compressed sides of the bar R' . The opposite end of the web, which may be made of silk or any other suitable material, is fastened to an ordinary spring-roller T , having end pins suitably journaled in the ends R^2 of the tubular side bar R . The end of the spring-roller is provided with a toothed pinion t , secured on one end pin and engaged by a lever U , which has a cam-shaped end near the pivot-pin u , whereby when the tooth U' of the lever is thrown down it will be down in engagement with the toothed wheel, and thus prevent it from rotating, and thereby hold the umbrella in the expanded position.

It will of course be understood that the side bars of the umbrella are ordinarily parallel with the longitudinal portion of the frame of the bicycle, but may be placed at any desired angle in relation to the frame compatible with the convenience of the rider.

When the cam-lever U has been released from contact with the toothed pinion t , the tendency of the web of the umbrella is to roll up upon the roller T , and this is actually effected by bringing the arms N gradually close together, when the side bar R' will be brought so as to straddle the side bar R , thus reducing the umbrella proper into very compact form. The side bars of the umbrella may be also swung around on the trunnion P , so as to bring one-half of them to lie adjacent to the supporting-arms. After this has been done the tube N^2 may be swung around on the quadrant M , so as to carry the supporting-arms and side bars down into a vertical position parallel with the standard. In this position the folded umbrella and its supporting parts will not extend down below the bottom reach in the gentleman's form, and consequently will be no hindrance to the propulsion of the pedal, and in the lady's form of course will be entirely out of the way. From actual experience and use I find that my now-

approved form is practical, light, and convenient.

Although I show the short standard E and tubular elbow F with a socket designed to support the main standard, it will of course be understood that various other devices might be supported in this simple device. It will also be understood that my umbrella may be applied with equal facility to vehicles of various kinds, such as boats, carriages, perambulators, &c.

What I claim as my invention is—

1. In a bicycle-umbrella, the combination with the standard having a toothed quadrant at the lower end, of the double clip embracing the top reach and designed to receive between the upper members the quadrantal end of the standard, means for holding the clip rigidly on the bicycle and the toothed block extending through one side of the clip normally engaging with the quadrant and provided with a stem extending through the opposite side and a knob and spring on such stem as and for the purpose specified.

2. The combination with the standard having a quadrantal lower end and double clip together with means for holding the quadrant and standard in place in the double clip, the opposing grooves in the bottom sides of the double clip, the supplemental hinged clip provided with grooves and the bar extending through the grooves and connected to lugs on the standard of the bicycle and means for holding the bottom ends of the clips tightly on the bar as and for the purpose specified.

3. The combination with the clip-socket and tubular extension thereof suitably secured to the frame of the bicycle and the split sleeve fitting therein and provided with an annular groove and set-screw extending into such groove from the clip-socket, of the main tubular standard provided with an internal grooved longitudinal rib or projection extending into the split in the sleeve, the clip at the top of the same and the internal extension-tube provided with an external longitudinal rib or projection fitting the groove in the main tube and an umbrella suitably supported on the top of the extension-tube as and for the purpose specified.

4. In an umbrella for bicycles, the combination with the main tubular standard and the extension-tube fitting and suitably held from turning therein and having the bottom end provided with an internally-threaded flange, of the threaded adjusting-tube extending through the flange and ball-bearings for the same at the lower end thereof suitably supported within the bottom of the main tubular standard and means for turning the adjusting-tube, so as to raise or lower the inner tubular extension within the main standard as and for the purpose specified.

5. In an umbrella for vehicles, the combination with the main tubular standard and extension-tube fitting and suitably held from turning therein and having the bottom pro-

vided with an internally-threaded flange, of a threaded adjusting-tube extending through the flange, the notch in the bottom of the adjusting-tube and a crank-spindle suitably held within the tube and designed to be thrown outwardly into the notch whereby the tube may be turned as and for the purpose specified.

6. The combination with the standard and the tube suitably held in position at the upper end thereof and provided with side lugs, of the umbrella, the supporting-arms pivotally connected to the side lugs, the inner extensions of the tube provided with upper jaws, the links connecting the jaws to the supporting-arms, the threaded inner adjusting-tube extending through the internally-threaded flanged bottom end of the extension-tube having the jaws at the upper end, suitable bearings for the adjusting-tube at the bottom of the supporting-tube and means for turning such tube as and for the purpose specified.

7. The combination with the standard and supporting-arms suitably held thereon, of the internal sleeve having the enlarged head and side slots and an end ring, the plug located in the sleeve and provided with a pin extending through the slots, a knurled ring connected to such pin, the pin extending upwardly through a hole in the ring, a spring situated beneath the bottom of the plug and the bottom of the sleeve, trunnions provided with a series of peripheral holes extending through the ring suitably held therein and provided with a right-angular projection at the top, the cross-bar secured to such projection and provided with divided rings at the end, the umbrella comprising the web and provided with side bars suitably held in the divided rings as and for the purpose specified.

8. The combination with the two telescopic portions of the standard having longitudinal ribs, the outer of which is provided with a downward extension, of a threaded tube extending through the closing-cap of the inner tube and provided with an extension jointed crank fitting within the same and forming a crank-handle for rotating the threaded adjacent tube as and for the purpose specified.

9. The combination with the standard made in two portions and means for preventing the rotation of the same, of the threaded adjacent tube suitably supported at the bottom of the standard provided with a lower notch and extending through the closing-cap of the inner standard and the jointed crank designed to lie in alignment within the tube and provided with a spring at its upper end to normally hold it in position as and for the purpose specified.

10. In an umbrella for bicycles, the combination with the main tubular standard and the extension-tube fitting and suitably held from turning therein and having the bottom end provided with an internally-threaded

flange, of the threaded adjusting-tube extending through the flange and means for turning the adjusting-tube, so as to raise or lower the inner tubular extension within the main standard as and for the purpose specified.

11. In an umbrella for bicycles, the combination with the standard having the outer and inner portions, the inner portion supporting the umbrella and both portions being provided with longitudinal projections whereby the inner portion is prevented from turning in the outer portion, a receiving socket or clip for the bottom of the standard and

15 means for completing the circle so that the standard can be turned within the socket or clip as specified.

12. In an umbrella for bicycles, the combination with the standard having the outer and inner portions, the inner portion supporting the umbrella and both portions being provided with longitudinal projections whereby the inner portion is prevented from turning in the outer portion, a receiving socket or clip for the bottom of the standard and

20 means whereby the standard is turned, so as to change its relative position to the top longitudinal portion of the frame to which the standard is fastened as specified.

25 13. The combination with an umbrella-standard and supporting-arms suitably connected to a tilt-controlling device, of a receiving portion affixed to said tilt-controlling device, a sliding portion to move on said receiving portion, an adjusting portion engag-

30 ing the sliding portion and journaled in the

receiving portion and means for turning the adjusting portion, the aforesaid sliding portion being pivotally connected by links to the supporting-arms whereby such arms are manipulated as specified.

14. In an umbrella-support the combination with the main standard having outer and inner portions designed to fit each other so as to prevent the inner from turning in the outer portion, of an adjusting portion connected to the inner and outer portions and means for turning the adjusting portion so as to extend or withdraw one portion within the other as specified.

15. In an umbrella-support the combination with the main standard having outer and inner portions designed to fit each other so as to prevent the inner from turning within the outer portion, a threaded adjusting portion engaging the lower end of the inner portion and journaled in the outer portion and means for turning the threaded adjusting portion so as to raise or lower the inner portion as specified.

16. In an umbrella for bicycles the combination with the tubular supporting-arms, of the depending swiveling portions connected to the side bars of the umbrella and of the bearings designed to receive them, such bearings being swiveled in the ends of the arms and suitably held in position.

GEORGE VALIANT.
